UNITED STATES PATENT OFFICE

ALONZO W. GEARHART, OF FRESNO, CALIFORNIA

FUEL OIL BURNER

Application filed March 18, 1929. Serial No. 347,860.

My invention relates to an oil burner adapted to gasify and burn fuel oil.

The object I have attained is the construction of a burner compact in form and one in which certain baffles are arranged to break up the circulating gaseous mixture so that the flame is fed by a current passing directly upward through the outlet opening, and an intense heat is created thereby. My present invention is an improvement on the form of burner described in my pending application Serial No. 257,569 filed February 28, 1928, for an oil burner.

In the drawings accompanying my application Fig. 1 is an outside view of a completed burner. Fig. 2 is a top sectional view thereof along the line 2—2 in Fig. 1 adapted to show the general direction of the gas formed by the fuel and the oxygen. Fig. 3 is a sectional view of the burner along a line 3—3 in Fig. 2. Fig. 4 is a separate side view of the bushing having baffles thereon which constitutes my invention. Fig. 5 is a bottom view of the bushing shown in Fig. 4. Figs. 6 and 7 are modified forms of Fig. 5.

Referring to said drawings, I have constructed an outer shell or housing 10 preferably tubular in shape, having a bottom 11, and an inwardly projecting flange 12 at the top, said shell forming a circular chamber 20 having a circular opening 120 at the top. The mixture to be consumed consists of liquid fuel and air or steam. The fuel intake is shown as 60. The air or steam is preferably introduced into chamber 20 under pressure (which may be accomplished by a fan) and through a pipe 13 which enters the chamber tangentially so the mixture will have a swirling helicoidal movement, the top opening 120 of the chamber being of less diameter than the inside diameter of the chamber. The direction of the current of the fuel and air mixture is shown by arrows 55.

For the purpose of more thoroughly breaking up the fuel and mixing it with the air or steam, I have provided a bushing 50 having a flange 51 adapting it to rest on the top of flange 12, said bushing having a plurality of depending baffles 52 which are adapted to change the course of the swirling gaseous

mixture so that it is directed toward the center of the opening 120 where it is consumed. The baffles 52 may be made curved as shown in Fig. 6, straight as shown in Fig. 4 or obliquely as shown in Fig. 7. Said baffles 55 should be positioned to direct the swirling fuel mixture toward the outlet opening.

In operating my device, air, or steam, enters the chamber together with a regulated supply of fuel which is given a swirling movement, tending to mix the elements. This mixture is necessarily forced through the top of the chamber, being the only outlet therefrom. Without my baffles this swirling movement would continue as it is ejected from the chamber, but my baffles modify this swirling movement by directing the currents from different sectors of the opening 120 toward the center of the opening where the several currents converge and pass directly upward, thus directly engaging the flame.

Having described my invention, I claim:

1. In combination with an oil burner having a circular chamber, a circular outlet opening at the top of the chamber, a fuel inlet into said chamber, means to introduce fluid into said chamber so that the fluid will have a swirling movement within the chamber and will mix the fuel therein, of a bushing fitted within the outlet opening, said bushing having a plurality of baffles depending from said bushing and within the chamber.

2. In an oil burner having a circular chamber and a fuel inlet, an outlet opening at the top of lesser diameter than the diameter of the chamber, means to introduce air to mix with the fuel in said chamber, said means introducing the air so that it has a swirling movement within the chamber, of baffles extending downward within the chamber adjacent to the outlet opening.

3. In an oil burner having a circular chamber and a fuel inlet, an outlet opening at the top of lesser diameter than the diameter of the chamber, means to introduce air to mix with the fuel in said chamber, said means introducing the air so that it has a swirling movement within the chamber, of baffles extending downward within the chamber adjacent to the outlet opening, said baffles being 100

positioned to direct the swirling fuel toward the outlet opening.

4. In an oil burner having a circular chamber and a fuel inlet, an outlet opening at the top of lesser diameter than the diameter of the chamber, means to introduce air to mix with the fuel in said chamber, said means introducing the air so that it has a swirling movement within the chamber, of baffles extending downward within the chamber adjacent to the outlet opening, said baffles having a curved face adapted and positioned to direct the swirling fuel toward the center of the discharge opening.
